RESERVE TRAY FOR REFRIGERATORS

Sophie Gónczi, New York, N. Y.

Application February 3, 1940, Serial No. 317,081

7 Claims. (Cl. 62—89)

This invention relates to new and useful improvements in a reserve tray for refrigerators.

More specifically, the invention proposes the construction of a reserve tray which is adapted to be mounted within the food compartment of a household refrigerator and upon and below the ice cube freezing compartment in a manner so that the cold air passing from the cube freezing compartment may pass into the reserve tray for causing the interior thereof to be chilled to the same temperature as the cube freezing compartment.

Another object of this invention proposes to characterize the reserve tray by a container mounted beneath the ice cube freezing compartment and into which meats may be stored, ice cream frozen, vegetables kept fresh, and which may be further used for storing ice cubes removed from the ice cube trays while other cubes are frozen in the trays.

Still further the invention proposes the provision of a shutter for controlling the passage of cold air from the ice cube freezing compartment to the reserve tray in a manner to control the inside temperature thereof.

A further object of this invention proposes the provision of a second shutter mounted upon the front of the reserve tray so that the same may be opened to permit the cold air from the interior of said reserve tray to pass into said food compartment in a manner to permit the cold air to escape from said reserve tray.

Still further the invention proposes the provision of a means extended between said shutters in a manner for closing one of said shutters when the other of said shutters is open, and vice versa, to control the temperature within said reserve tray as desired.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is an elevational view of a household refrigerator having a reserve tray, according to this invention, mounted on the ice cube freezing compartment.

Fig. 2 is an enlarged detailed view of a portion of Fig. 1.

Fig. 3 is a horizontal sectional view on the line 3—3 of Fig. 2.

Fig. 4 is a vertical sectional view on the line 4—4 of Fig. 2.

Fig. 5 is an enlarged detailed view looking in the direction of the line 5—5 of Fig. 2.

Fig. 6 is an enlarged elevational view similar to a portion of Fig. 2 but illustrating a modification of the invention.

Fig. 7 is a vertical sectional view substantially on the line 7—7 of Fig. 6.

Fig. 8 is a fragmentary view of the refrigerator, illustrating another form of the invention.

The reserve tray for refrigerators is to be used in conjunction with a household refrigerator 10 having a food storage compartment 10a closed by means of a hingedly mounted door 11. The refrigerator 10 has an ice cube freezing compartment 12 mounted within the top portion thereof. This compartment 12 is formed with a front opening into which a plurality of ice trays are adapted to be inserted and which is normally closed by means of a removable door 13 having a pair of handles 13a for facilitating the removal thereof.

The reserve tray, according to this invention, is in the form of a compartment or container 14 mounted upon the bottom of the ice cube freezing compartment by means of strip 15 extending along the sides thereof. Screws 16 are passed through the strips 15 and into the respective faces of the ice cube compartment 12 and the reserve tray 14 for holding the tray in position upon the bottom thereof. This reserve tray 14 is formed with a front opening 14a connecting with the interior thereof and which is closed by means of a removable door 17. This door adjacent its top and bottom edges is provided with handles 17a which are adapted to be manually grasped and used for removing the door when it is desired to open the said front opening.

A novel means is provided for holding the door 17 in position across the front opening of the reserve tray 14. To accomplish this the reserve tray is provided with an outwardly extending flange 14a around the front opening thereof and over which an inwardly extending flange 17b is formed on the door 17 is adapted to engage. The flange 14a is provided with a plurality of outwardly extending pins 18 which are adapted to engage downwardly inclined slots 19 formed in the flange 17b of the door 17. The bottom of the door 17 is not formed with any flange for permitting the door 17 to be moved downwards and inwards relative to the reserve tray for engaging the cover 17 across the front opening of the tray.

A shutter is provided for controlling the passage of cold air from the freezing compartment 12 to the reserve tray 14. This shutter comprises a slide 20 mounted within a groove 20a formed 5 partially within the top face of the reserve tray 14 and the bottom face of the ice cube freezing compartment 12. This tray is slidably mounted by means of pins 21 extending from the bottom face of the groove 20a and engaging complementary slots 22 formed in the slide 20. The slide 20 is provided with a plurality of openings 23 which are adapted to be aligned or disaligned with a plurality of complementary openings 24 formed in the top of the reserve tray 14 and bottom of the ice cube freezing compartment 12. The front edge of the slide 20 is provided with a knob 25 for facilitating the movement thereof to align and disalign the openings 23 and 24. When the slide 20 is in its outwardly extended 10 position as shown in Fig. 3, the openings are disaligned, and when pushed inwards the openings become aligned, forming a free passage for cold air from the freezing compartment 12 to the reserve tray 14.

25 The door 17 of the freezing compartment 14 is further provided with a second shutter for controlling the passage of air from the interior of the reserve tray to the interior of the food compartment 10a of the refrigerator 10. This shutter is in the form of a disc 26 rotatively supported on the door 17 by means of a pin 27. The disc 26 is formed with moon-shaped opening 26a which is adapted to be aligned with a complementary moon-shaped opening 17c formed 30 in the front of the tray 14 and more preferably in the door 17. When these openings are aligned the cold air within the reserve tray 14 may freely pass therethrough and into the interior of the food compartment 10a. The disc is provided with 35 a handle 28 for facilitating the rotation of the disc 26 to align and disalign the openings 26a and 17c.

The operation of this form of the invention is as follows:

40 When it is desired to have the interior of the reserve tray 14 extremely cold for the purpose of preserving ice cubes, chilling drinks, freezing ice cream or other similar uses requiring extreme cold, the disc 26 is rotated to disalign the openings 26a and 17c and the slide 20 is moved to align the openings 23 and 24 to permit the cold air to freely pass from the ice cube freezing compartment 12 to the reserve tray 14 for the thoroughly chilling the interior thereof. At such 45 times when it is desired to preserve vegetables, meats or other foodstuffs without freezing the same, and still maintain the foods at a temperature lower than the temperature of the food compartment 10a, the same is placed within the reserve tray 14 and the slide 20 is moved outwards to disalign the openings 23 and 24 to prevent the free passage of cold air from the ice cube freezing compartment to the reserve tray. At the same time the disc 26 is rotated to align the 50 openings 26a and 17c to permit the cold air to pass from the reserve tray to cause the temperature within the tray to rise to a point where the foodstuffs placed therein will not freeze.

According to the modification of the invention 55 shown in Figs. 6 and 7, the construction of the reserve tray is similar to that previously described except that the reserve tray 14' is in the form of a container removably mounted upon the bottom of the ice cube freezing compartment 60 70 75 in a manner to permit the same to be removed

therefrom when desired. To accomplish this the bottom of the ice cube freezing compartment 12 is formed with downwardly extending flanges 12a having inwardly extending tracks 12b. These tracks 12b engage complementary grooves 14b formed in the sides of the reserve tray 14' for slidably and releasably holding the reserve tray in position upon the bottom of the ice cube freezing compartment.

The interior of this reserve tray 14' is further 10 provided with an inwardly extending flange 14c upon which a removable shelf 30 is adapted to be rested. This shelf 30 is so constructed that it may be removed when desired through the top opening of the reserve tray 14'. The front of 15 the reserve tray is further provided with a handle 31 fixedly secured to the top edge thereof and which may be grasped for sliding the tray out of the refrigerator when desired.

This form of the invention is further provided 20 with a means for closing the shutter 20' arranged between the ice cube freezing compartment and the reserve tray 14' when the shutter 26 is opened and for opening the shutter 20' when the shutter 26 is closed. To accomplish this the pin 21' which 25 rotatively supports the shutter 26 carries an enlarged cam 32. This cam is contained within an inwardly extending slot 33 formed in the front wall of the reserve tray 14'. Further, the shutter 20' is formed at one side with an extending lug 30 20b carrying a pin 20c. The space between the ice cube freezing compartment 12 and the reserve tray 14' is formed with an enlarged opening 33a within which a bell crank 34 is pivotally supported. One arm of the bell crank 34 is provided with an elongated slot 34a engaging the pin 20c of the lug 20b. The junction of the arms of the bell crank 34 is provided with a slot 34b which slidably and rotatively engages a pin 35 35 extending between the walls of the enlarged opening 33.

The shutter 26 is provided with a means for 40 limiting its rotation through substantially 180° and comprises a pin 36 mounted upon the front wall of the reserve tray 14' and which engages a 180° 45 arcuately shaped cutout formed on a portion of the periphery of the disc shaped shutter 26. The pin 36 is adapted to engage the ends of the arcuately shaped cutout for limiting the rotation of this disc.

The operation of this form of the invention 50 is as follows:

As shown in Fig. 6 the shutter 26 is in its open position and the shutter 20' is in its closed position. Assume that it is desired to reverse the 55 position of these shutters for permitting the reserve tray to be used for storing ice cubes or other food material requiring an extremely low temperature. To accomplish this the material to be stored within the reserve tray are placed there- 60 in and the tray is engaged in position upon the bottom of the ice cube freezing compartment 12. The handle 28 of the disc shaped shutter 26 is then manually grasped and the shutter 26 rotated to cause the same to engage across the 65 opening 17c in the front of the reserve tray 14' for closing this opening. This movement also caused the cam 32 to rotate until it engages the bottom end of the free arm of the bell crank 34. Upon engagement, the bell crank 34 was moved 70 slightly upwards until the pin 35 struck against the bottom end of the slot 34b. After striking, further movement of the cam 32 caused the bell crank 34 to be pivoted about the bottom end of the slot 34b, pulling the shutter 20' to its open 75

position. After passing the free end of the bell crank 34 the bell crank will move down due to the force of gravity until the pin 35 rests against the top end of the slot 34b.

5 When it is desired to restore the shutters 26 and 20' to the positions shown in Fig. 6, it is merely necessary to rotate the disc shaped shutter 26 back to its starting position which will also cause the cam 32 to be rotated which will 10 strike against the free arm of the bell crank 34 which is dropped down to a position to be struck by the cam causing the bell crank to be pivoted and urge the shutter 20' back to its closed position. When long periods of time are 15 permitted to elapse between movements of the slide 20' and slide becomes frozen in position it might be necessary to defrost the refrigerator to free the slide.

As shown in Fig. 8 the reserve tray 14 may 20 also be used as a separate unit and be independent from the compartments 12. In this form of the invention, the freezing pipe 40 is extended at 41 to surround the reserve tray 14. The freezing pipes 40 and 41 may be joined or disconnected by suitable fittings 42.

It is also to be understood that the shelf 30 may be raised or lowered or entirely removed to 25 make room for larger products. Any desired number of shelves may be used and they may 30 be constructed of wire-mesh or any other suitable material.

35 While I have illustrated and described the preferred embodiments of my invention, it is to be understood that I do not limit myself to the precise construction herein disclosed and the right is reserved to all changes and modifications coming within the scope of the invention as defined in the appended claims.

Having thus described my invention, what I 40 claim as new, and desire to secure by United States Letters Patent is:

1. In combination with a household refrigerator having a food storage compartment and an ice cube freezing compartment therein, a reserve 45 tray compartment within said storage compartment and mounted on and beneath said freezing compartment, a shutter controlling an air passage from the freezing compartment to the tray compartment, and another shutter controlling 50 an air passage from the tray compartment to said food storage compartment.

2. In combination with a household refrigerator having a food storage compartment and an ice cube freezing compartment therein, a reserve 55 tray compartment within said storage compartment and mounted on and beneath said freezing compartment, a shutter controlling an air passage from the freezing compartment to the tray compartment, and another shutter controlling 60 an air passage from the tray compartment to said food storage compartment, said reserve tray compartment being in the form of a container mounted upon the bottom of the ice cube freezing compartment.

65 3. In combination with a household refrigerator having a food storage compartment and an ice cube freezing compartment therein, a reserve tray compartment within said storage compartment and mounted on and beneath said freezing 70 compartment, a shutter controlling an air passage from the freezing compartment to the tray compartment, and another shutter controlling an air passage from the tray compartment to said food storage compartment, said first mentioned shutter comprising a slide supported with-

5 in a groove partially formed in the top face of said reserve tray on the bottom face of said freezing compartment, said slide being formed with openings alignable with complementarily arranged openings formed in said reserve tray and said freezing compartment, and means for limiting the movement of said slide to a position in which said openings will be aligned or disaligned.

4. In combination with a household refrigerator having a food storage compartment and an ice cube freezing compartment therein, a reserve tray compartment within said storage compartment and mounted on and beneath said freezing compartment, a shutter controlling an air passage from the freezing compartment to the tray compartment, and another shutter controlling an air passage from the tray compartment to said food storage compartment, said first mentioned shutter comprising a slide supported within a groove partially formed in the top face of said reserve tray on the bottom face of said freezing compartment, said slide being formed with openings alignable with complementarily arranged openings formed in said reserve tray and said freezing compartment, and means for limiting the movement of said slide to a position in which said openings will be aligned or disaligned, said means comprising pins 20 extending from the bottom face of said groove 25 and engaging complementary elongated slots 30 formed in said slide.

5. In combination with a household refrigerator having a food storage compartment and an ice cube freezing compartment therein, a reserve tray compartment within said storage compartment and mounted on and beneath said freezing compartment, a shutter controlling an air passage from the freezing compartment to the tray compartment, and another shutter controlling an air passage from the tray compartment to said food storage compartment, said first mentioned shutter comprising a slide supported within a groove partially formed in the top face of said reserve tray on the bottom 45 face of said freezing compartment, said slide being formed with openings alignable with complementarily arranged openings formed in said reserve tray and said freezing compartment, and means for limiting the movement of said 50 slide to a position in which said openings will be aligned or disaligned, said means comprising pins extending from the bottom face of said groove 55 and engaging complementary elongated slots formed in said slide, said slide being formed with a handle for facilitating the movement thereof to align and disalign said openings.

6. In combination with a household refrigerator having a food storage compartment and an ice cube freezing compartment therein, a reserve tray compartment within said storage compartment and mounted on and beneath said freezing compartment, a shutter controlling an air passage from the freezing compartment to the tray compartment, and another shutter controlling an air passage from the tray compartment to said food storage compartment, said second shutter comprising a disc shaped member 60 rotatively mounted upon the face of said reserve tray, said disc shaped member being formed with an opening adapted to be aligned and disaligned with a complementary opening formed in said reserve tray, said reserve tray being formed with a front opening closed by 70 75

means of a removable door, and said second shutter being formed on said door.

7. In combination with a household refrigerator having a food storage compartment and an ice cube freezing compartment therein, a reserve tray compartment within said storage compartment and mounted on and beneath said freezing compartment, a shutter controlling an air passage from the freezing compartment to the tray

compartment, and another shutter controlling an air passage from the tray compartment to said food storage compartment, and means for closing said first-named shutter when said second-named shutter is opened, and opening the first-named shutter when said second-named shutter is closed. 5

SOPHIE GÓNCZI.
